JOHN SAWYER HOYLE, OF WARE, MASSACHUSETTS.

ROLLER-BEARING PRESSING ROLLER FOR DRAWING AND SPINNING FRAMES.

Application filed January 17, 1925. Serial No. 3,123.

To all whom it may concern:

Be it known that I, JOHN S. HOYLE, a citizen of the United States of America, and a resident of Ware, in the county of 5 Hampshire and State of Massachusetts, have invented new and Improved Roller-Bearing Pressing Rollers for Drawing and Spinning Frames, of which the following is a description.

10 My invention relates to drawing and spinning frames and particularly to the pressing roller thereof.

15 The general object of my invention is to provide a pressing roller for drawing and spinning frames equipped with a roller bearing, whereby to bring about improved results in the action of the pressing roller or pressure roller on the strand of wool, worsted, cotton, or other animal or vegetable 20 fibers.

Reference is to be had to the accompanying drawings forming a part of this specification, it being understood that the drawings are merely illustrative of one example 25 of the invention.

Figure 1 is a schematic view showing the assemblage of a drawing frame embodying my improved pressure roller;

Figure 2 is an elevation showing two of 30 the pressure rollers and their associated driving rollers;

Figure 3 is a central longitudinal section taken through the pressure roller;

Figure 4 is a face view of the pressure 35 roller with the shaft in section as indicated by the line 4-4, Figure 3.

Referring to Figure 1, the numeral 10 indicates a roving spool; 11, 12 an upper and a lower roller between which the strand 13 40 of wool or the like passes, the upper roller 11 being a pressure roller. Two pairs of intermediate rollers 14 are shown between the rollers of each pair of which the strand 13 passes. The numeral 15 indicates my improved pressure roller between which and a lower roller 16 the strand 13 passes, the roller 16 being a driven roller and driving 45 the roller 15 by friction. After passing between the rollers 15, 16, the strand 13 passes through an opening 17 in the frame A to be formed into a cop 18.

In accordance with my invention I provide a pressure roller assemblage in which a plurality of pressure rollers 15 in practice 55 correspond in number with the number of strands 13; said rollers 15 are roller bear-

ing pressure rollers and each one of the pressure rollers 15 can turn about the axis of the pressure roller shaft 19. The two rollers 16 shown on the drive shaft 20 in association 60 with the rollers 15, in Figure 2, drive by friction said rollers 15 but each roller 15 is free to accommodate itself to its work independent of other rollers 15 coaxial therewith. Each roller bearing roller 15 makes 65 with its associated roller 16 an assemblage independent of the other pressure roller and drive roller units, the strands 13 are effectively gripped at all times and tensioned. On the other hand in the usual arrangement in 70 which a single solid pressure roller is employed, the strands 13 are not treated individually since there is liable at all times to be unequal contact of the pressure roller with the various strands so that one is tensioned to a different degree from the others and indeed it may be that the tension is marked on one strand or a number of strands 75 and is negligible in others of the strands.

In each roller 15 is a hardened bushing 80 21 forming with the hardened shaft 19 a raceway for an annular series of hardened roller bearings 22. In practice any approved tension means may be provided, there being a tension rod B shown as part of the 85 assemblage, said rod being connected with a part of the frame A and having in practice spring means, not shown.

In practice collars 23 are provided on the shaft 19 at each side of each pressure roller 90 15, said collars having set screws 24 and serving to prevent axial displacement of the pressure rollers along the shaft 19 as well as serving to prevent endwise displacement 95 of the bearing rollers.

I would state in conclusion that while the illustrated example constitutes a practical embodiment of my invention, I do not limit myself strictly to the exact details herein illustrated, since, manifestly, the same can be considerably varied without departure 100 from the spirit of the invention as defined in the appended claim.

Having thus described my invention, I 105 claim:

In a pressure roller assemblage for drawing and spinning frames, a pressure roller shaft, a plurality of separate pressure rollers mounted thereon, a drive shaft common to said pressure rollers, hardened bushings in each pressure roller, roller bearings in each pressure roller having direct rolling contact 110

with the pressure roller shaft, said pressure rollers being adapted to turn independently of each other, and drive rollers on the drive shaft in frictional driving engagement with said pressure rollers; together with flat collars on the pressure roller shaft at each side of the latter, and of larger diameter than the bushings, set screws in said collars

to bind the same on said shaft, said collars preventing axial displacement of said pressure rollers and serving to retain the bearing rollers against endwise movement, and a common tensioning means acting on the pressure roller shaft to apply pressure to all of said rollers. 10

JOHN SAWYER HOYLE.
